ASA BENTON WELCH, OF ATLANTA, GEORGIA

DIRIGIBLE HEADLIGHT

Application filed August 31, 1927. Serial No. 216,667.

This invention relates to headlights and particularly to a headlight that may be turned on its support as the vehicle turns.

One object of the invention is that it may be readily attached to a locomotive or vehicle of the ordinary construction.

Another advantage is that the parts may easily be kept in repair and wear taken up by tightening certain bolts used in the construction of the invention.

With these and other objects as will appear as the description proceeds, I will now proceed to describe the invention in connection with the drawings in which:

15 Figure 1 is a side view of the invention as attached to a locomotive.

Fig. 2 is a side sectional view of my invention.

Fig. 3 is a view of a male supporting member.

Fig. 4 is a view of a female supporting member.

Fig. 5 is a view of the upper rotating arm shown in section in Fig. 2.

25 Fig. 6 is a detail view of another arm shown in section in the upper part of Fig. 2.

Fig. 7 is a view of a lower arm shown in the lower part of Fig. 2, and,

Fig. 8 is a view of the bracket shown at 30 the lower part of Fig. 2.

1 represents a headlight casing which, as best shown in Fig. 2, is bolted to a male member or base 2 by bolts 3 with their heads countersunk in the member 2. 4 is a female base member into the upper surface of which a flange 5 of the male member is fitted. 6 is a pivot for the casing 1 which may be welded or otherwise rigidly attached to the casing so that when the pivot member 6 is rotated as 35 hereinafter described it will rotate with it the casing 1 of the headlight enclosed therein and the male member 2 attached thereto. 7 is a bracket which may be attached to the front of the locomotive as indicated in Fig.

40 1 and has integral with it an arm 8 through which a rod 9 passes. Attached to the top end of the rod 9 is an arm 10 having therein a slot 11 near its left hand end as shown in Figs. 2 and 6. Rigidly attached to the pivot member 6 at its lower end is another arm 12

having vertical bolt holes 13 spaced apart near its left hand end as shown in Figs. 2 and 5, through which a bolt 14 may pass with its lower end resting in the slot 11 of the arm below. The object of having a plurality of 55 holes 13 is to adjust the bolt 14 at various distances from the pivot member 6 in order to get the proper amount of turning motion of the headlight.

The female member 4 may be bolted to an 60 arm 17 of the bracket 7 and I preferably provide a collar 18 around the pivot member 6 between the arm 12 and the arm 17 of the bracket 7.

To take up any wear in the parts I provide bolt holes 19 in the arm 12 with bolts therethrough which may be tightened occasionally so as to firmly hold the bolt 14 and the pivot member 6 so that as the arm 12 is rotated as hereinafter described, it will cause 65 the pivot member 6 to rotate and thus turn the headlight as desired. A similar bolt hole 20 with a suitable bolt therein is useful for keeping the arm 10 securely clamped to the rod 9.

When the headlight is applied to a locomotive as shown in Figs. 1 and 2, I preferably bolt a collar 21 to a suitable support on the top of a truck through which the rod 9 passes and thence through a hole in the top of the truck down to an arm 22 fastened securely to the bottom of the rod 9 and kept tight around the rod 9 by a bolt 23 passed through a bolt hole 24 and to keep the bolt 23 tight, I may provide a vertical bolt 25 70 passing through a bolt hole 26 in the arm 22. In the left hand end of the arm 22 I provide a bolt hole 27 through which a bolt 28 passes and extends through a slot 30 in a bracket 31 held to a portion of the truck 75 32 of a locomotive. The bracket 31 may be bolted to the member 32 of the truck by bolts 35.

In order to hold the bolt 28 tightly in the arm 22, I provide a bolt 37 passing 80 through a bolt hole 38.

It will be clear from the foregoing that as the truck comes to a curve and its direction changed, the bracket 31 will operate through the bolt 28 and arm 22 to turn the rod 9 and 85 100

through its arm 10 the bolt 14 and the arm 12 to turn the pivot member 6 which being rigidly fastened to the headlight casing 1 will cause the latter to turn and turn the light.

The depression in the female member 4 may be supplied with oil to relieve the friction between the female member 4 and the male member 2.

10 Whenever the parts become loose by reason of wear, by tightening up the bolts in the arms 12 and 22, the lost motion may be taken up and the arms kept tight around the pivot member 6 and the rod 9. It will thus be
15 seen that I have provided a headlight that will turn with the truck and wherein the lost motion may be taken up and the parts kept in working order, and the invention may be easily applied to the ordinary locomotive
20 without material change in the existing device.

Having described my invention, what I claim as new is:

1. Operating mechanism for a headlight
25 comprising a casing, a pivoted member rigidly attached to the casing, an arm rigidly attached to said pivoted member and having a plurality of vertical bolt holes therein, a two part extensible rod having pivotal
30 connection with a locomotive truck frame and carrying an upper and lower arm with means for taking up lost motion between the rod and arms, a pin in the lower arm, a projection on the truck and a slot connection
35 between said projection on the truck and said pin said upper arm having a slot adapted to receive a pin inserted in either of said vertical bolt holes in the arm carried by the pivoted member.
- 40 2. A headlight operating mechanism comprising a headlight casing, a support consisting of a bracket having an upper and lower arm extending outwardly from said support, the upper arm of the bracket supporting said
45 casing, a male member secured to the bottom of the casing, a cooperating female member secured to the upper arm of the support, a pivot member rigidly attached to the center of the bottom of the headlight casing and
50 passing downwardly through the centers of both said male and female members, a rod with upper and lower arms detachably and adjustably clamped to said rod, means to take up lost motion between both said arms
55 and said rod, said rod being journaled in said lower arm of said bracket, an arm attached to said pivot member and having a series of holes therein, a pin adapted to fit in said holes, said upper arm having a slot therein
60 to receive said pins when inserted in either hole and a bracket attached to a truck and having a pin and slot connection with the lower arm on said rod.

65 In testimony whereof I affix my signature.
ASA BENTON WELCH.
